UNITED STATES PATENT OFFICE.

AUGUSTUS H. JONES, OF MERIDEN, CONNECTICUT, ASSIGNOR TO THE MERIDEN BRONZE COMPANY, OF SAME PLACE.

LAMP-BURNER.

SPECIFICATION forming part of Letters Patent No. 554,936, dated February 18, 1896.

Application filed July 22, 1895. Serial No. 556,668. (No model.)

To all whom it may concern:

Be it known that I, AUGUSTUS H. JONES, of Meriden, in the county of New Haven and State of Connecticut, have invented a new 5 Improvement in Lamp-Burners; and I do hereby declare the following, when taken in connection with the accompanying drawings and the letters of reference marked thereon, to be a full, clear, and exact description of the 10 same, and which said drawings constitute part of this specification, and represent, in—

Figure 1, a view in side elevation of a lamp-burner constructed in accordance with my invention with its gallery in its depressed position; Fig. 2, a similar view with the gallery in its elevated or lighting position; Fig. 3, a 15 partial view of the burner in vertical central section showing the gallery in its elevated position; Fig. 4, a broken view in side elevation of the upper end of the outer wick-tube to show the circumferential groove formed therein.

My invention relates to an improvement in that class of lamp-burners which are adapted, 20 by reason of having vertically-movable galleries, to permit the application of a lighted taper to the wick without the removal of the chimney, the object being to provide, of the class described, a simple, durable, effective 25 and conveniently-operated burner at a low cost for manufacture.

With these ends in view my invention consists in a lamp-burner having certain details of construction, as will be hereinafter 30 described and pointed out in the claim.

In carrying out my invention I furnish the gallery A of the burner with a depending tube A', which substantially corresponds in diameter to the diameter of the central opening of the gallery and the upper portion of which has formed in it one or more large 35 taper or lighting openings A², which are designed to permit a lighted taper to be applied to the wick when the gallery is raised. The

tube of the particular burner shown has two 40 of these openings, but one will answer the purpose, and if desired there may be more than two. The said tube is also provided with one or more spring-fingers A³, the extreme upper ends of which are bent to form 45 horizontally-arranged locking-ribs a, as

shown. These fingers are formed integral with the tube and located in the lower ends of the said openings which are virtually continued by the vertical slots a' leading downward from the lower ends of the openings on opposite sides of the fingers for forming the same. The burner shown has two of these fingers, but one will do, although more than two may be employed if desired. The said 50 tube is adapted in internal diameter to fit over the outer wick-tube B of the burner, so as to slide up and down thereupon, the said outer wick-tube being secured at its lower end, in the usual manner, to the perforated 55 burner body or skirt C. The upper end of the said outer wick-tube is constructed with a circumferential groove b, into which the locking-ribs a of the fingers A³ spring when the gallery, and hence the tube A', is raised 60 sufficiently high to bring the ribs into range with the groove. That portion of the tube lying directly below the groove is slightly beveled, as at B', to make the depression of the 65 gallery easier, by requiring the spring-fingers 70 A³ to be sprung less when the ribs ride out of the groove.

It will be readily understood that in the normal condition of the burner the gallery A is depressed, so that its edge rests upon 75 the edge of the skirt. At this time the locking-ribs of the spring-fingers are engaged with the exterior surface of the outer wick-tube B. To elevate the gallery its edge is grasped, and it is lifted until the locking-ribs 80 of its spring-fingers spring into the groove of the outer wick-tube, whereby the gallery is supported without other aid, in suitable position for the insertion of a lighted taper through one of the openings A' to light the 85 wick. Then after the wick has been lighted a slight downward pressure upon the gallery 90 springs the ribs of the fingers out of the groove and permits the gallery to go back to its normal position.

If it is desired for any reason to remove the gallery altogether from the burner, that may be done by drawing the parts apart with sufficient force to cause the ribs of the spring-fingers to ride out of the groove and over the 95 extreme upper edge of the outer wick-tube.

It is apparent that in carrying out my in-

vention some variations from the exact construction shown and set forth may be made. I would therefore have it understood that I do not limit myself to such specific construction, but hold myself at liberty to make such alterations as fairly fall within the spirit and scope of my invention.

Having fully described my invention, what I claim as new, and desire to secure by Letters Patent, is—

In a lamp-burner, the combination with the gallery and the body thereof, of a tube secured to and depending from the said gallery, substantially corresponding in diameter to the central opening thereof, and constructed in its upper portion with one or more lighting-openings which expose the wick when the gallery is raised, and also constructed with one or more integral spring-fingers located in the

lower ends of the said opening or openings and exerting a constant effort to spring inward, and an outer wick-tube extending upward from the said body, and having its upper end constructed with an inwardly-extending circumferential groove into which the said fingers spring when the gallery is raised for holding the same in its elevated or lighting position, and also for preventing the gallery from being detached from the said tube, substantially as described.

In testimony whereof I have signed this specification in the presence of two subscribing witnesses.

AUGUSTUS H. JONES.
